UNITED STATES PATENT OFFICE.

ROLLIN M. HYDE, OF DETROIT, MICHIGAN, ASSIGNOR TO McCORD RADIATOR & MFG. CO., OF DETROIT, MICHIGAN, A CORPORATION OF MAINE.

REFRIGERATING UNIT.

Application filed July 12, 1926. Serial No. 121,820.

This invention relates to refrigerating units for electric refrigerators.

One object of my invention is to make the unit of sheet metal so that the hollow sections through which the refrigerant circulates may be made from stampings, and thus be produced cheaper than cast units or units formed of headers and tubes as heretofore generally employed.

10 Another object of my invention is to stamp the front and rear walls of each section from sheet metal and secure such walls together about their meeting edges by lock seams so as to obtain leak proof joints.

15 A further object of my invention is to connect the sections of the units together for circulation of the refrigerant therethrough by providing lock joints between the connections at the respective sections, thereby obtaining leak proof joints as well as utilizing the connections as means for spacing the sections apart to permit the passage of air between the same, as required in the operation of a unit.

20 25 A further object of my invention is to provide a container supporting fixture for use with the chilling compartment of the unit such fixture being removable from such compartment so that containers larger than those supported by the fixture may be used in the compartment.

The invention consists further in the matters hereinafter described and claimed.

In the accompanying drawings—

30 35 Fig. 1 is a front view of a refrigerating unit constructed in accordance with my invention;

Fig. 2 is a side view of the same;

40 Fig. 3 is an enlarged vertical sectional view taken on the indirect line 3—3 of Fig. 1 to show the control valve within the unit;

Fig. 4 is a horizontal sectional view taken on line 4—4 of Fig. 3;

45 Fig. 5 is a front view of the unit, showing the container supporting fixture in the chilling compartment thereof;

Fig. 6 is a horizontal sectional view taken on line 6—6 of Fig. 5; and

50 Fig. 7 is a vertical section taken on line 7—7 of Fig. 6.

As shown in the drawings, the refrigerating unit comprises a plurality of hollow sections 1, 1 preferably vertically disposed and joined together for the circulation of

a refrigerant therethrough. Each section 55 has front and rear walls 2, 3 stamped or pressed from sheet metal of the shape desired and having within the margins thereof upper and lower openings 4, 5. The sections are joined together with their respective upper and lower openings in alignment to form the float and chilling compartments, respectively, of the unit.

60 The walls 2, 3 of each section are provided with marginal flanges 6, 7 about their outer edges and also about the edges of the opening 5, said flanges being secured together for connecting these walls. In the drawings, I have shown these flanges connected together by lock seams, such being accomplished by having one flange, namely, the one 7, made long enough so as to be bent over and crimped about the other flange 6. This provides a leak proof connection for the two 65 walls of the section.

70 75 The walls 2, 3 of each section are provided about their upper openings 4 with outwardly drawn tubular projections 8, 8. The sections are arranged with these projections meeting so as to space the sections apart for the passage of air between them, as required in the operation of the unit. These projections 8 may be secured together in any manner desired so as to connect the sections together for the flow of the refrigerant therethrough. In Fig. 3, I have shown the projections 8 connected together by lock 80 85 seams, this being accomplished by providing the meeting edges of the projections with surrounding flanges 9, 10 with the latter made long enough so as to be bent over and crimped about the shorter flange 9.

85 90 In stamping out the rear wall for the rearmost section of the unit, the tubular projection 8 of that wall is left unpierced or closed so as to provide a closure for the rear end of the float compartment, as indicated in Fig. 2. The front wall of the front section of the unit is cut out or pierced at the opening 4, but not to the full extent of 95 the opening, so as to provide a relatively wide flange 11, as shown in Fig. 3. A plate 12 is secured on the outside of this flange by a number of bolts 13, 13, as shown. Threaded bosses 14, 14 are provided on the 100 inside of this wall to receive the inner ends of the screws, these bosses being connected together by a ring as shown. The plate 12

is provided with inlet and outlet bosses, 15, 16, to which suitable inlet and outlet pipes are connected, as indicated in Fig. 3. The boss 15 continues into a boss 17 extending 5 rearward from the plate and through the connecting ring of the bosses 14. The boss 17 is provided with an inlet passage 18, which opens into the float compartment, such opening being controlled by a needle 10 valve 19. Said valve is slidably mounted in a lower boss 20 on the plate 12 and extending inward therefrom. To raise and lower the valve, a float 22 is located within the compartment formed within the hollow sections 15 by the alignment of the openings 4. The float 22 has its stem 23 fulcrumed at 24 to the plate 12 on the inside. Said stem has a vertical slot 25 for the valve 19 to pass through it, said valve being connected with 20 the stem by a pin 26 working in elongated horizontal openings 27 in the stem, as shown in detail in Fig. 4.

The outlet 16 of the unit is connected with the suction side of the compressor, while 25 the inlet 15 is connected with the refrigerant supply, the float 22 functioning to operate the valve 19 as the level of the refrigerant varies within the hollow sections of the unit, in accordance with the operation 30 of devices of this kind.

The chilling compartment, as provided by the aligned openings 5, 5 of the several sections, is large enough to receive a fairly good size vessel or container 28, as indicated in dotted lines in Fig. 1. In order that this compartment may accommodate a number of smaller containers, such as may be required when making pans of ice or freezing ice-cream, etc., I provide a fixture 40 which may be inserted in and removed from this compartment. This fixture is illustrated in Figs. 5 to 7. It comprises two side members 29, 29, both made alike. Each member is stamped from sheet metal and 45 has a length to extend through the chilling compartment from front to rear. Each side member has end flanges 30, 30 bent back from the body 31 of the member, said flanges gripping or snapping over the locked flanges 6, 7 of the front and rearmost sections 1, 1 of the unit, as illustrated in Fig. 5. The body portion of each member is 50 stamped out to provide a plurality of flanges 32, 32, which when the member is in place 55 in the chilling compartment extend inward and align with the corresponding flanges on the other side member, as shown in Fig. 5. These flanges provide supports for a number of containers 33, 33, as shown in Fig. 5. 60 When it is desired to place a larger container in the chilling compartment, the fixture just described is removed therefrom.

To support the unit above the floor of the ice box in which the unit is placed, I provide the unit with a number of feet 34, 34.

These are in the form of adjusting screws so that the unit may be leveled. These screws have relatively large heads and their threaded shanks or stems take into parts 35, 35 associated with side members 36, 36 70 arranged beneath the sections of the unit. These side members 36 are preferably formed of sheet metal and are stamped to have generally V-shape and are arranged with their side walls extending upwardly, 75 said walls being cut out at a number of places in their length to accommodate the lower portions of the sections of the unit, as clearly shown in Fig. 2.

By having the unit made entirely of sheet metal, it is not only light in weight, but it may be economically and cheaply made because the walls of the various sections may be readily and quickly stamped from sheet metal, scrap metal being used when available. The relatively thin walls provided by the sheet metal allow for radiation, this being helped by having the lock flanges 6, 7 of the unit extend beyond the walls thereof, so as to provide additional extended radiating surfaces. Moreover, the units may be enameled on the outside so as to give a pleasing and sanitary appearance and thus permit the units to be installed in ice-boxes without the use of shields to hide them, as is the case with cast units or those made of tubing, as heretofore employed.

The details of structure may be variously changed and modified without departing from the spirit and scope of my invention. Moreover the flanges 6, 7 of each unit could be welded in place of being crimped.

I claim as my invention:

1. A refrigerating unit for refrigerating machines, comprising a plurality of hollow sections joined together to contain a refrigerant, each section having front and rear walls formed of sheet metal with registering openings within the margins of said walls, said sections being arranged with the registering openings in the walls of the respective sections aligned to form the chilling compartment of the units, the walls of each section being secured together about their outer edges and about the edges of the registering openings therein, said unit having refrigerant inlet and outlet means above said chilling compartment.

2. A refrigerating unit for refrigerating machines, comprising a plurality of hollow sections, each section having front and rear walls formed of sheet metal with upper and lower registering openings within the margins of said walls, said sections being joined together at the upper openings in the walls thereof and having the lower openings in said walls in alignment to form the chilling compartment of the unit, the walls of each section being secured together about their outer edges and about the edges of the lower

openings therein, said unit having refrigerant inlet and outlet means in line with said upper openings.

3. A refrigerating unit for refrigerating machines, comprising a plurality of hollow sections joined together to contain a refrigerant, each section having front and rear walls formed of sheet metal with registering openings within the margins of said walls, said sections being arranged with the registering openings in the walls of the respective sections aligned to form the chilling compartment of the unit, the walls of the several sections being flanged about their outer edges and about the edges of their registering openings, the flanges of the walls of the respective sections being secured together with the flanges extending outward from the walls of the sections and forming extended radiating surfaces of the unit, and the latter having refrigerant inlet and outlet means above the chilling compartment. 55

4. A refrigerating unit for refrigerating machines, comprising a plurality of hollow sections joined together to contain a refrigerant, each section having front and rear walls formed of sheet metal with registering openings within the margins of said walls, said sections being arranged with the registering openings in the walls of the respective sections aligned to form the chilling compartment of the unit, the walls of the several sections being secured together about their outer edges and about the edges of their registering openings with flanges at said openings extending into the same, and a pair of members insertible in said compartment at the opposite sides thereof and having means to snap over the flanges of certain of said sections, and container supports carried by said members. 60

5. A refrigerating unit for refrigerating machines, comprising a plurality of hollow sections, each section having front and rear walls stamped from sheet metal with upper and lower registering openings within the margins of said walls, said sections being arranged with the openings in the walls of the respective sections in alignment with the lower openings forming the chilling com- 65

partment of the unit, the walls of the several sections being secured together about their outer edges and about the edges of their lower openings, and tubular portions drawn from the walls at the upper openings and being secured together to provide communication between the sections and space them apart so that air may circulate between the same, said unit having inlet and outlet means for the refrigerant in line with said upper openings. 70

6. A refrigerating unit for refrigerating machines, comprising a plurality of hollow sections formed of sheet metal and connected to contain a refrigerant, said sections having aligned openings forming the chilling compartment of the unit, said unit having refrigerant inlet and outlet openings above said chilling compartment, and valve means carried by the unit for controlling the supply of refrigerant to the sections, through said inlet opening. 75

7. A refrigerating unit for refrigerating machines, comprising a plurality of hollow sections formed of sheet metal and connected together to contain a refrigerant and to provide a communicating passage between them, and a float valve located in said passage for controlling the supply of refrigerant to the sections, the latter being formed to provide a chilling compartment for the unit. 80

8. A refrigerating unit for refrigerating machines, comprising a plurality of hollow sections, each section having front and rear walls formed from sheet metal with upper and lower openings in each of said walls, said sections being joined together at the upper openings in the walls thereof to contain a refrigerant and having the lower openings in said walls aligned to form the chilling compartment of the unit, the walls of each section being secured together about their outer edges and about the edges of the lower openings therein, and a float valve located in the passage provided by the upper openings for controlling the supply of refrigerant to the sections. 85 90 95

In testimony whereof I affix my signature this 6th day of July, 1926.

ROLLIN M. HYDE.
